(57) **CLAIM**

The ornamental design for a uterine manipulator, as shown and described.

DESCRIPTION

FIG. 1 is a bottom left side isometric view of a uterine manipulator in accordance with the new design;

FIG. 2 is a left side isometric view thereof;

FIG. 3 is a right side isometric view thereof;

FIG. 4 is a top plan view thereof;

FIG. 5 is a bottom plan view thereof;

FIG. 6 is an enlarged front elevational view thereof; and,

FIG. 7 is an enlarged rear elevational view thereof.

The broken lines shown in FIGS. 1 and 5 are for the purpose of illustrating portions of the uterine manipulator that form no part of the claimed design.
